UNITED STATES PATENT OFFICE.

BERTHOLD HUBER, OF TAUNTON, MASSACHUSETTS.

SHEET-DELIVERING APPARATUS FOR PRINTING-PRESSES.

SPECIFICATION forming part of Letters Patent No. 311,432, dated January 27, 1885.

Application filed July 7, 1882. (No model.)

To all whom it may concern:

Be it known that I, BERTHOLD HUBER, of Taunton, in the county of Bristol and State of Massachusetts, have invented a certain new and useful Improvement in Sheet-Delivery Apparatus for Printing-Presses, of which the following is a specification.

My invention is applicable to cylinder printing-presses, and relates to the arrangement of the fly for taking the sheets from the tapes and depositing them upon the fly-board.

The invention consists in the combination, with a fly having a horizontal shaft, which is fulcrumed at one side of the press or near one end of the shaft, so that it may be swung in a horizontal plane from a position crosswise of the press toward a position lengthwise of the press, of devices for giving such swinging movement of the fly-shaft and at the same time turning the shaft so as to reverse the fly-fingers and deposit the sheet.

The invention also consists in novel details of construction and combinations of parts in the mechanism for imparting the before-described double movement to the fly-shaft.

In the accompanying drawings, Figure 1 represents a vertical longitudinal section of a part of a press embodying my improvement. Fig. 2 represents a plan thereof, the side frames only being in horizontal section. Fig. 3 represents an end elevation, and Fig. 4 represents a detail view on a larger scale of one of the receiving-wheels and tape wheels or rollers.

Similar letters of reference designate corresponding parts in all the figures.

A designates the foundation-plate of the press, and A' designates the side frames supported thereon.

B designates the impression-cylinder mounted in bearings in the side frames, A'. The cylinder is provided with ordinary grippers, a, for taking the sheets from the feed-board C, the grippers being operated in any ordinary way. Below the feed-board is arranged a shaft, D, which may be operated by a hand-crank, D', or other suitable means, and the shaft D carries a spur-wheel, D², which engages with a wheel, B', of double its size upon the cylinder-shaft, and thereby imparts motion to the cylinder.

Upon the shaft D are a number of receiving-

wheels, D³, and through these wheels extends a gripper-shaft, b, provided with a gripper, c, for each wheel, which is received in a recess, c', in the side of the wheel, as shown in Fig. 4. The grippers c are secured directly upon and are supported by the gripper-shaft b. The grippers c take the sheet from the impression-cylinder in a well-known manner; but as they in themselves form no part of my invention, I have not shown their operating mechanism.

Adjacent to the receiving-wheels D³ is a shaft or bar, d, extending transversely across the press, and carrying a number of upwardly-extending arms, d', which serve as supports for rollers or wheels e, which are small enough so that they will be received between the gripper-shaft b, and the periphery of the receiving-wheels D³.

Around the small rollers or wheels e are passed tapes or bands f, the upper sides of which are tangential to the receiving-wheels D³, and these tapes also pass around larger rollers or wheels g upon a shaft, g', as best shown in Figs. 1 and 2. The shaft g' is rotated positively—as here shown, from the shaft D—by means of a belt, g², passing around a pulley, g³, upon the shaft D, and a pulley, g⁴, on the shaft g'. The relative sizes of the pulleys g³ and the rollers or wheels e g should be so proportioned that the tapes will travel at exactly the same speed as the peripheral velocity of the receiving-wheels D³, so that the freshly-printed sheet will not be smutted by the tapes or bands, as will be the case if said tapes do not travel at the same speed as the sheet is delivered from the wheels D³.

E designates the horizontal fly-shaft, and h the fly-fingers.

F designates a vertical shaft at the side of the press and opposite the end of the fly-shaft. The shaft F is made in two parts, as shown in dotted lines in Fig. 3, and these two parts are connected by a cross-head, F'. The fly-shaft E passes horizontally through this cross-head and between the ends of the two parts of the shaft F, and thus the two shafts are connected together, so that the shaft F forms a fulcrum on which the shaft E turns.

G designates the fly-board, which is not placed directly in front of the press, but at one side and in advance thereof. The shaft F

is adapted to turn in bearings *i*, and by so turning it the fly-shaft *E* is swung outward in an arc-shaped path, and is brought to the position shown in the dotted lines in Fig. 2.

5 Upon the shaft *E* is a bevel-wheel, *j*, or a segment of a wheel, and this engages with a stationary gear-segment, *j'*, secured on the bed *A*. Consequently it will be understood that as the shaft *E* is swung bodily outward it is 10 also turned by the gear-segment *j* turning on the stationary segment *j'*, and reverses the fly to deposit the printed sheet on the fly-board *G*. By a reverse movement of the shaft *F* the fly-shaft is swung back into its former position, and is turned so as to bring the fingers into position to receive the sheet.

Any suitable mechanism may be employed to give the shaft *F* the desired rotation alternately in opposite directions. In this example of my invention I provide a cam, *H*, upon the shaft of the cylinder *B*, and a horizontally-moving bar, *I*, having a roller, *k*, at one end entering the groove in the cam, and a rack, *l*, at the other end engaging with a segment-gear, 25 *m*, on the shaft *F*. The bar *I* is slotted or bifurcated to receive the cylinder-shaft through it, and as the bar is reciprocated by the cam *H* the shaft *F* will be turned alternately in reverse directions.

30 In the operation of my press the sheet is taken by the grippers of the impression-cylinder and is carried downward to receive the impression from the form on the bed. When the head of the sheet reaches the receiving-wheels *D*, their grippers, which have previously been opened, are closed on the head of

the sheet, and by them the sheet is transferred onto the receiving-wheels. As the head of the sheet reaches the tapes the grippers of the wheels *D* are opened and the sheet moves 40 downward onto the fly, and when nearly the whole sheet is on the fly the fly-shaft is swung outward and turned to deposit the sheet onto the fly-board *G*.

What I claim as my invention, and desire 45 to secure by Letters Patent, is—

1. In a printing-press, the combination, with a fly having a shaft fulcrumed at one side of the press, of devices, substantially as described, for imparting a swinging motion to said fly-shaft upon its fulcrum, and for instantaneously 50 rotating it to reverse the fly and deposit the sheet, substantially as specified.

2. In a printing-press, the combination, with a fly-shaft and an upright shaft to which the 55 fly-shaft is connected, so that the upright shaft forms a fulcrum for the fly-shaft, of devices, substantially such as described, for imparting a rotary motion alternately in opposite directions to the upright shaft, a gear upon the fly-shaft, and a stationary gear engaging therewith and serving to turn the fly-shaft, substantially as specified.

3. The combination of the fly-shaft *E*, the upright shaft *F*, the gear *j*, the stationary gear 60 *j'*, the cam *H*, the rack-bar *I*, and the gear *m* on the shaft *F*, substantially as specified.

BERTHOLD HUBER.
